RAILROAD SNOWPLOW

Filed Dec. 15, 1926

2 Sheets-Sheet 1

comprising; two inner and two outer longitudinal sills; a rear end sill, formed as a one piece casting; and a front end sill, formed of three aligned one piece castings, the intermediate casting being disposed between, and removably attached to, the inner sills, and constituting a base for engine shaft supports.

9. A railroad snow plow supporting bed, comprising; two inner and two outer longitudinal sills; a rear end sill, formed as a one piece casting, and removably attached to said sills; a front end sill, comprising a one piece casting, embodying a base for engine shaft supports; and a bolster, box shape in cross section, formed as a one piece casting, and removably attached to two of said sills.

10. A bolster for railroad snow plow supporting beds, cast in one piece, box shape in cross section, and embodying a flange for supporting the bottom edge of a boiler expansion plate.

11. A bolster for railroad snow plow supporting beds, cast in one piece, box shape in cross section, and comprising; a flange for supporting the bottom edge of a boiler expansion plate, and a depending, intermediate portion, constituting a center plate, said portion having a bore for a center pin.

12. A railroad snow plow supporting bed, comprising; two inner and two outer longitudinal sills; and an end sill, formed as a one piece casting, and having an intermediate and two outer portions, the intermediate portion having a draft pocket and two walls extended at a right angle to the length of the end sill, adapted for bolting to

the inner longitudinal sills, the two outer portions of the end sill being box shape in cross section and extending to the outer longitudinal sills.

13. A railroad snow plow supporting bed, comprising; two inner and two outer longitudinal sills; and an end sill, formed as a one piece casting, and having an intermediate and two outer portions, the intermediate portion having a draft pocket, and two walls, extended at a right angle to the length of the end sill, and adapted for bolting to the inner longitudinal sills, said intermediate portion having a raised face for supporting a buffer plate; the two outer portions of the end sill being box shape in cross section and extending to the longitudinal sills.

14. A railroad snow plow supporting bed, comprising; two inner and two outer longitudinal sills; and an end sill, formed as a one piece casting, and having an intermediate and two outer portions, the intermediate portion having a draft pocket, and two walls extended at a right angle to the length of the end sill, and adapted for bolting to the inner longitudinal sills, said intermediate portion having a flange for supporting the lower edge of a boiler expansion plate; the two outer portions of the end sill being box shape in cross section and extending to the longitudinal sills.

15. An end sill for railroad snow plow beds, formed as an integral casting, and embodying a support for the lower edge of a boiler expansion plate.

JOHN S. PAYNE.

Patented Jan. 31, 1928.

UNITED STATES PATENT OFFICE.

JOHN S. PAYNE, OF MIDLAND PARK BOROUGH, NEW JERSEY.

RAILROAD SNOWPLOW.

Application filed December 15, 1926. Serial No. 154,880.

My invention more particularly relates to the supporting beds of railroad snow plows, and has for an object to provide a bed structure, certain parts of which are formed as integral, or one-piece, castings, which structure possesses a higher degree of strength, rigidity, and durability, in proportion to its weight, than those heretofore known, and which will materially increase the factor of safety, and effect a substantial economy in manufacturing and maintenance costs.

The improvement claimed is hereinafter fully set forth.

In the accompanying drawings: Figure 1, is a plan view of a railroad snow plow bed, embodying my invention; Fig. 2, a longitudinal, vertical section of the same, taken on the line, *a—a*, of Fig. 1; Fig. 3, a partial transverse section on the line, *b—b*, of Fig. 2; Fig. 4, a view in perspective of the rear end sill casting; and, Fig. 5, a view in perspective of the combined engine bed and front sill casting.

In the practice of my invention, referring descriptively to the specific embodiment thereof which is herein exemplified, the snow plow bed is shown as comprising two inner longitudinal sills, 10, of the flat slab type, and two outer longitudinal sills, 11, of channel shape in cross section. The rear ends of the longitudinal sills are connected to an end sill, 12.

The rear end sill, 12, is a one piece casting, comprising a vertical transverse end wall, 13, having a raised flat face, 14, for the attachment of a suitable buffer plate, not shown. Two vertical longitudinal walls, 15, extend forwardly from the end wall, 13, and are provided with bolt holes, 16, for the attaching bolts, 17, by which the end sill is secured to the inner sills, 10.

The end wall and the longitudinal walls are connected together by a horizontal wall, 18, which is disposed intermediate the height of the end wall, and is formed with a bore, 19, for the draw bar pin, not shown. Disposed below the horizontal wall, 18, are three spaced horizontal walls, 20, 21, and, 22, each formed with a boss, 23, having a central bore, 24, for the draw bar pin. The four horizontal walls are connected together across their width by two spaced vertical longitudinally extending walls, 25. The horizontal walls, 18, 20, and, 21, are of similar length, and the lowermost horizontal wall, 22, is shorter

than the others, terminating at the longitudinal walls, 25. The four horizontal walls are also connected together at their front ends by a vertical transverse wall, 26, which is formed with a transverse flange, 27, having bolt holes for receiving the bolts, 28, by which the back, boiler expansion plate, 29, is attached. The flange, 27, is also formed with a transverse recess, the bottom wall of which, provides a bearing surface for the bottom edge of the expansion plate, which construction relieves the bolts of shearing stresses.

The described construction provides two pockets, 30 and, 31, in the end sill, one above the other for the reception of the draw bar.

The vertical walls, 25, extend to the top of the end wall, and their upper edges slope therefrom down until they meet the horizontal wall, 18.

A transverse reinforcing web, 32, extends from the inner face of each of the longitudinal walls, 15, its bottom being connected throughout its length to the horizontal wall, 18, and its top edge sloping from the top of the longitudinal wall down until it meets the horizontal wall, 18.

Projecting transversely beyond the outer face of each of the longitudinal walls, 15, is a box shape extension, having two side walls, 33 and, 34, a bottom wall, 35, a top wall, 36, and an end wall, 37. The side walls, 34, have suitable bolt holes for the attachment of the angle brackets, 38, by which the outer longitudinal sills, 11, are bolt connected to the rear end sill.

The inner longitudinal sills, 10, are connected together, intermediate their length, by a box shape, one-piece, bolster casting, 95 having two side walls, 39, two end walls, 41, a top wall, 42, and a bottom wall. Each end wall extends above the top wall and beyond the side walls, to provide a bolting flange, 43, for the bolts, 44, by which the bolster is attached to the inner sills, 10. Two transverse reinforcing webs extend from the tops of the flanges, 44, to the top wall, 42.

The bottom wall is formed centrally with a depending portion, 45, constituting a center plate by which the snow plow bed is supported on the rear truck. The center plate is provided with a bore, 46, for the center pin, not shown, and the top wall, 42, is provided with an elongated slot, 47, to permit insertion thereof.

To provide for the attachment of the front boiler expansion plate, the bolster casting is formed with a transverse flange, 48, which slopes downwardly and outwardly from the top wall, 42, and is provided with bolt holes for the bolts, 49, and a transverse recess, which receives the bottom of the forward expansion plate. The bottom edge of the expansion plate bears on the bottom wall of the recess, thus relieving the bolts, 49, of shearing stresses.

The front end of the snow plow bed comprises an end sill formed of two outer and one intermediate section, the two outer sections, 50, being integral box shape castings fitted between and bolted to the inner and the outer longitudinal sills, and the intermediate section, 51, being an integral casting adapted to constitute, in addition to a part of the front sill, a bed for supporting the engine.

The intermediate section, 51, comprises a main horizontal plate, 52, extending from one of the inner longitudinal sills, 10, to the other. Depending from the bottom of the main plate, on each side thereof, is a vertical longitudinal flange, 53, having bolt holes, 54, for the bolts, 55, by which the intermediate section is attached to the inner sills.

To provide for bolting the intermediate section to the outer sections, the main plate, 52, is extended laterally at its front end beyond the longitudinal flanges, 53, to provide horizontal flanges, 56, adapted to overlie the outer sections, 50, and having bolt holes, 57, for bolting to the outer sections.

Disposed on the top of the main plate at each side of the rear end thereof, is a vertical longitudinal flange, 58, having bolt holes, 59, bolting to the smoke box saddle brace, not shown. Spaced from and disposed between the flanges, 58, are two spaced vertical longitudinal flanges, 60, each having at its top, a horizontal flange, 61, adapted to support the pillow blocks on which the rear end of the rotor shaft is mounted. Bolt holes, 62, are provided in the flanges, 61, for bolting to the pillow blocks. Three vertical transverse webs, 63, serve to reinforce the flanges, 58, 60 and 61.

The main plate, 52, forwardly of the flanges, 60, is formed with a depression, 64, to provide a clearance for the bevel gear on the rotor shaft.

At each side of the main plate, forwardly of the depression, 64, is a standard, 65, having a transversely extending dovetail recess, for receiving the dovetail on the stub shaft bearing blocks. Each standard has, at its top, on each side of the recess, a horizontal transverse flange, 66, formed with bolt holes, 67, for bolting to the stub shaft bearing blocks.

Intermediate the dovetail standards, is a raised base, 68, having two spaced transverse

horizontal flanges, each formed with bolt holes, 69, for bolting to the end bearings of the stub shaft and the central bearing for the rotor shaft. Two spaced transverse vertical webs, 70, serve to reinforce the connection between the raised base and the dovetail standards.

At the front end of the main plate, at each side thereof, is a vertical longitudinal flange, 71, having bolt holes, 72, for bolting to a rotor housing brace. Intermediate the flanges, 71, are two spaced vertical longitudinal flanges, 73, each having bolt holes, 74, for bolting to a rotor housing brace. From the inner side of each of the flanges, 73, extends a horizontal flange, 75. The latter flanges serve to support the front pillow block of the rotor shaft, and are each provided with bolt holes, 76, for bolting thereto. The connection between the flanges, 71, 73, and 75, is reinforced by two transverse webs, 77, and by the vertical wall, 78, which constitutes the front face of the intermediate section of the front sill.

I claim as my invention and desire to secure by Letters Patent:

1. An end sill for railroad snow plow supporting beds, embodying a base for an engine shaft support.

2. An end sill for railroad snow plow supporting beds, comprising a one piece casting, embodying a base for an engine shaft support.

3. An end sill for railroad snow plow supporting beds, comprising a one piece casting, and embodying flanges constituting bases for engine shaft supports.

4. An end sill for railroad snow plow supporting beds, formed of three aligned one piece castings, the intermediate casting embodying a base for engine shaft supports.

5. An end sill for railroad snow plow supporting beds, formed of three aligned one piece castings, the intermediate casting embodying horizontal faces constituting bases for engine shaft supports.

6. An end sill for railroad snow plow supporting beds, formed of three aligned one piece castings, the intermediate casting embodying flanges for supporting rotor shaft pillow blocks, and flanges for supporting stub shaft bearing blocks.

7. A railroad snow plow supporting bed, comprising; two inner and two outer longitudinal sills; and an end sill embodying two outer and one intermediate section, each formed as an integral casting and each of the outer sections being disposed between, and removably attached to an inner and an outer longitudinal sill, the intermediate section being disposed between the two center sills, and removably attached thereto, said intermediate section embodying a base for an engine shaft support.

8. A railroad snow plow supporting bed,
